UNITED STATES PATENT OFFICE.

ALEXANDER WALKER, OF MOUNT GAMBIER, SOUTH AUSTRALIA, AUSTRALIA.

PENCIL-CASE AND OTHER CYLINDER.

No. 924,406.

Specification of Letters Patent.

Patented June 8, 1909.

Application filed June 6, 1908. Serial No. 437,180.

To all whom it may concern:

Be it known that I, ALEXANDER WALKER, a subject of the King of Great Britain and Ireland, &c., residing at Mount Gambier, in 5 the State of South Australia, Commonwealth of Australia, have invented certain new and useful Improvements (for educational purposes) in Pencil-Cases and other Cylinders; and I do hereby declare the following to be a 10 full, clear, and exact description of the invention, such as will enable others skilled in the art to which it appertains to make and use the same.

This invention relates to a novelty in pencil boxes or other cylindrical hollow cases; and it consists in the combination therewith of certain devices for facilitating educational calculation problems, by answering or by yielding immediate answers to any of a series 20 of predetermined questions. The information exhibited is thus interrelated, one part with other parts.

It is known that calculating apparatus has already been devised in which a perforated 25 cylinder is movable to show a desired answer through one hole, but my object is to produce a simpler and better construction than any known to me.

In the accompanying drawings Figure 1 is 30 a side elevation of an embodiment of my device, partly broken away to show interior construction. Fig. 2 is a side elevation of a slideable and rotatable,—and (in some cases) removable sleeve; and Fig. 3 represents an 35 end view showing (partly in transverse section) portion of the sleeve and contained parts, and showing a modification.

In these views A is a cylindrical outer sleeve. It has exactly three perforations 40 and no more and it has these longitudinally set in one straight line. Each hole is made of any suitable size and shape for its purpose. If there were more holes it would lead to confusion and error on the part of children, and 45 even other persons, using the device; hence the number of holes is three, and their position is an advantage for another purpose as it leaves almost the whole surface of the sleeve unperforated and smooth, and usable 50 as a ruler. The sleeve has at will any suitable additions as a scale E, or a plurality of scales, and any desired printed matter. It, and all other parts, are of any suitable materials, and sizes, and in any suitable variety of 55 color.

As shown in Fig. 1 there is the symbol of

multiplication preceded and followed by the word "Factor", between the left hand hole B, and the intermediate hole C; and there is the symbol of equality and the word "Product" 60 to the left of hole D. The words "Factor" and "Product" are omitted in some cases. In Fig. 2 the words "At" and "Each" appear. No claim is made to particular wording, the same being omittable or variable 65 according to circumstances. In some cases I insert the words "Days" or "Hours" before "At" and insert the abbreviations "L.S.D." (or other money signs) near holes C and D, so that prices of goods, amounts of 70 wages and so forth may be exhibited. Casting K has any suitable end caps, or cap. A removable cap shown has a body M, and a flange N, corresponding with flange O at the other end of the box, so that the device may 75 roll on a plane without sleeve A touching it. Body M of the cap may screw on or otherwise, and be outside cylinder K or, as shown, inside. There is provided in some cases an end ridge or transverse band L, integral with 80 the cylinder; but a separate ring fitted on is in some cases used. Part L is useful as a boundary to the end J of the band or cylinder F. The latter (part of which is seen in Fig. 1 through a gap broken in the sleeve) contains 85 series of horizontal lines of characters or figures. Each line consists of—as illustrated—on the left two series, G and H, of factors, and on the right one series, I of products. The factors and products are all so positioned that whatever factors appear in holes 90 B and C their product appears in hole D.

Turning of and sliding of sleeve A in contact with figures or the like G, H, I is prevented by having protective bands, rings or 95 transverse members. In Fig. 1 the gap in the sleeve discloses rings R, screwed on; but they may be held on in any other suitable manner as by adhesive,—or spring pressure. In some cases these rings are ridges or projections embossed on material F; or projecting ridges or members are integrally formed or affixed upon cylinder K. In some cases part F is in a plurality of separate (say three) sheets properly assembled but divided by 100 these ridges. One advantage of having projections is that characters G, H, I, cannot become worn or rubbed off by movement of the sleeve.

The material of part F is paper, celluloid, 110 composition, or metal; tendency for it to slip longitudinally is prevented as by ridge

2
L, or bands R. In some cases characters G, H, I, are printed direct upon cylinder K. And in some cases there is a recess Q in cylinder K to receive the ends of sheet or sheets 5 F containing the numbers, or items of inter-related information. Sides P of recess Q, are integral with cylinder K; or are formed by any suitable attachment. The ends of the paper or the like are gripped in the recess 10 by locating the sides of the latter close to one another, or the ends are held in by inserting a feather. There may be a plurality of sheets affixed around the casing K at one time, but only the outer one would be in use 15 then.

In practice the spaces between characters G, H, I, vary according to the maker's preference. When parts A, F, are removed (and sometimes R) there is left a pen and 20 pencil (or other hollow) case usable as a ruler. Some minor details above described may be omitted at will.

What I claim as my invention and desire to secure by Letters Patent of the United 25 States is:—

1. A calculating device comprising in combination, an outer casing having an interior cylindrical wall provided with openings spaced apart from each other, and a 30 member disposed in said casing and reduced in size with respect to the diameter of the interior wall of said casing, said inner member having peripherally disposed bearing elements engaging the inner wall of said 35 casing to maintain said member and casing in concentric relation with respect to each other and permit relative rotation and longitudinal adjustment of said member and casing, said element forming the sole bearing 40 means between said casing and members, said member having a plurality of calculating characters disposed upon its periphery to be disclosed through said openings.

2. A calculating device comprising in

combination, an outer casing having a cylindrical interior wall and provided with openings spaced apart from each other and having its ends entirely open, and a member disposed in said casing and relatively reduced with respect to the diameter of the inner 45 walls thereof and of greater length and projecting through the open ends of said casing, said inner member having peripherally disposed bearing elements engaging the inner wall of said casing to maintain said member and casing in concentric relation with respect 50 to each other and permit relative rotation and longitudinal adjustment thereof, said element forming the sole bearing means between said casing and member, said member 55 having a plurality of calculating characters disposed upon its periphery to be disclosed through said openings.

3. A calculating device comprising in combination, a hollow outer cylinder open at 60 both ends and provided with spaced openings in its wall, an inner cylinder disposed in said outer cylinder and reduced in diameter with respect thereto, said inner cylinder being of greater length than the outer cylinder 65 and projecting beyond the ends thereof, said inner cylinder having annular bearing members disposed on its periphery and engaging the interior of said outer cylinder to hold said cylinders in concentric relation with respect 70 to each other and permit relative rotation and sliding adjustment thereof, said inner cylinder being provided with calculating characters arranged to be disclosed through 75 said openings, and caps on said inner cylinders limiting longitudinal movement thereof with respect to said outer cylinder.

In testimony whereof, I affix my signature in presence of two witnesses.

ALEXANDER WALKER.
